UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,838, dated December 4, 1894.

Application filed October 29, 1894. Serial No. 527,957. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or other woven fabric is fully illustrated in the accompanying drawing and it consists essentially of the two sets 10 of stripes alternating with each other, one set of stripes having four prominent secondary stripes and the other having a series of narrow stripes giving the effect of a dark stripe alternating with a light stripe on a tinted 15 back ground.

The stripe N is composed of four narrow dark stripes n^1 , and four light stripes n^2 on one side of each dark stripe and four tinted stripes n^3 on the opposite side of each dark 20 stripe.

The stripe M consists of three heavy stripes

m^1 separated by white stripes m^2 and a well defined narrow tinted stripe m^3 . The border of said stripe is composed of three narrow stripes m^4 , m^5 and m^6 , light, dark and tinted 25 respectively.

The back ground between the stripes M and N is tinted and in the back ground on each side of the stripe M are two narrow stripes o^1 giving the effect clearly shown in the drawing. 30

I claim—

The design for woven fabric as herein described and clearly illustrated in the accompanying drawing.

In testimony whereof I have signed my 35 name to this specification in the presence of two subscribing witnesses.

JOHN B. MORGAN.
